OUTFIRE CONTROL

Arthur V. Sampsel, Mendota, Ill., assignor to
Sears, Roebuck and Co., Chicago, Ill., a corpora-
tion of New York

Application April 9, 1940, Serial No. 328,740

9 Claims. (Cl. 236—9)

This invention relates to controls for heating devices.

In furnaces and other heating apparatus having automatic fuel feed, unless the fuel feed is stopped when the fire dies, there may be considerable waste of fuel, with the attendant inconvenience of cleaning out the excess fuel, and even injury or destruction of the furnace wall or other structure.

It is accordingly an object of my invention to provide against such a contingency.

It is a further object to provide an improved means for preventing undesired feed of fuel, whether solid or fluid, when the fire is out.

It is also an object to provide a stoker-fired furnace equipped with a hold-fire control, i. e., a device periodically operating the stoker for preventing a fire from going out, and with an out-fire control, i. e., a device preventing operation of the stoker when for any reason the fire goes out.

Another object is to provide for temperature-controlled periodic operation of a stoker to prevent a fire from dying and to circumvent such operation when for any reason something in or associated with the heating system is out of order.

A further object is to provide a temperature-controlled device for preventing undesired feed of fuel to a heating apparatus.

It is still another object to provide a common temperature control for both a hold-fire control and an out-fire control.

It is a still further object to provide a fluid operated heating apparatus with an out-fire switch located where the heat is not of a destructive nature.

It is also an object to provide a signal giving notice that something in or associated with the heating system is amiss.

Another object is to provide an improved thermostat construction.

Further objects and advantages of the invention will appear as the description proceeds.

The invention will be better understood upon reference to the accompanying drawings, in which:

Fig. 1 is a diagrammatic view of a stoker circuit employing mercury tube hold-fire and out-fire controls.

Fig. 2 is a fragmentary sectional view showing a wind-box installation of the hold-fire and out-fire control switches of Fig. 1.

Fig. 3 is a plan view of the detent mechanism appearing in Fig. 2.

Fig. 4 is a view similar to Fig. 1 but with the out-fire control omitted.

Fig. 5 is a view similar to Fig. 1 but with the hold-fire control omitted.

Fig. 6 is a diagrammatic view similar to Fig. 1 but employing gas to control the hold-fire and out-fire switches.

Fig. 7 is a view similar to Fig. 6 but shows the hold-fire switch clock-controlled.

Fig. 8 is a view similar to Fig. 7 but omits the hold-fire switch and shows a gas-controlled out-fire snap switch.

Fig. 9 is similar to Fig. 5 but shows a thermometer type out-fire control switch.

Fig. 10 is a view similar to Fig. 1, but of a modified circuit including an out-fire alarm.

Fig. 11 is similar to Fig. 10, but relates to an out-fire alarm for a gas, oil or other fluid fuel burner.

Fig. 12 is a front elevation of a double blade thermostat embodying features of my invention.

Fig. 13 is a side elevation of the same.

Fig. 14 is a partially schematic view taken as indicated by the line 14—14 in Fig. 12.

Fig. 15 is a front elevation taken as indicated by the line 15—15 in Fig. 13, the mounting plate being omitted.

Fig. 16 is a top plan view of Fig. 15.

Fig. 17 is a fragmentary sectional view taken as indicated by the line 17—17 in Fig. 13.

Fig. 18 is a fragmentary sectional view taken as indicated by the line 18—18 in Fig. 17.

Fig. 19 is a rear elevation taken as indicated by the line 19—19 in Fig. 13.

Fig. 20 is a sectional view taken as indicated by the line 20—20 in Fig. 15.

Referring now more particularly to the drawings, there is shown in Fig. 1 a stoker circuit in which energy from the feed line at 25 passes from the hot side 26 of the line through a hand switch 27, which is normally closed, and a transformer primary 28 to the ground 32. The transformer secondary 34, a hold-fire control switch 35, an out-fire control switch 36 and a relay coil 37 are all in series. A room thermostat switch 38 is in parallel with the hold-fire control switch 35.

Also in series with the line and the hand switch 27 is a limit switch 40, which remains closed as long as the furnace temperature is not excessive, a spring-opened relay switch 41 and a stoker 42.

The hold-fire control switch 35 is provided to keep the fire from going out, as it is likely to do particularly in mild weather when for relatively long periods the room thermostat does not call for heat, i. e., does not cause operation of the stoker. The switch 35 is accordingly adjusted to close when the fire is at or just above the dying

temperature, i. e., when the wind-box temperature is about 85° F., for example, and to open when the fire is at a somewhat higher temperature, i. e., when the wind-box temperature is about 100° F., for example.

The out-fire control switch 36 is provided to open and thereby stop the stoker when the fire is out. It is accordingly adjusted to be closed as long as the fire is alive. The switches 35 and 36 may be mounted to turn in unison, as will appear.

When the furnace is cold, the hold-fire switch 35 is closed and the out-fire switch 36 is open, so that the relay coil is not energized and accordingly the stoker-controlling relay switch 41 is open. To start the stoker, the out-fire switch 36 is manually moved until it is closed, thereby completing the relay circuit which closes the stoker switch 41. A fire is thereupon kindled in the furnace, the switch 36 being held in closed position manually or by a suitable retainer for a suitable length of time, say, fifteen or twenty minutes, more or less, while the furnace warms up. Then the switch 36 may be released, and at such time the furnace will be sufficiently warm to maintain the switch 36 automatically in closed position, where the switch will remain until the fire goes out or is dying.

Since while the fire is alive the out-fire switch 36 remains closed, it follows that unless the room thermostat 38 calls for heat, the operation of the stoker while the fire is alive will be controlled by the hold-fire control switch 35. When either or both of the switches 35 and 38 call for heat, the stoker will operate because the relay switch 41 will be closed, and when both of the switches 35 and 38 are open the stoker will not operate because the relay switch 41 will be open. When the fire dies, the out-fire switch 36 opens, thereby opening the relay switch 41 regardless whether the hold-fire switch 35 or the thermostat switch 38 or both call for heat, and a detent 44 (Figs. 1 and 2) serves to retain the switch 36 in open position until the switch is manually moved past the detent and held in closed position as set forth above.

Should the wind-box temperature upon death of the fire exceed that at which the out-fire switch 36 opens, and should the hold-fire switch 35 or the thermostat switch 38 at such time be closed, the stoker may operate even though the fire is out, but in that event the period will be short, say about a minute, more or less, because the cool air blown into the fire-box will bring the temperature of the wind-box rapidly to the point, say 70° F., at which the out-fire switch 36 opens.

When the fire is rekindled, the switch 36 must be manually reset, as explained above.

The switches 35 and 36 may be mounted on a common shaft 45 connected to a thermo-sensitive coil 46 protected by a metal or other suitable housing or shell 47 secured in the interior 48 of a wind-box 49 about a burner 50. A rise in wind-box temperature affects the coil in such manner as to urge the out-fire switch 36 and initially the hold-fire switch toward closed positions. As the wind-box temperature rises above say, 100° F., the out-fire switch 36 continues to be closed but the hold-fire switch moves to open position.

The hold-fire control switch may be operated otherwise, as by a clock, and the out-fire control switch may be operated otherwise, as by a gas bellows, as will appear more fully hereinafter.

The out-fire control switch 36 of Figs. 1 and 2 may be eliminated simply by omitting the same and/or joining the contacts of said switch, as

shown in Fig. 4. Then the stoker operates whenever the hold-fire switch 35 or the thermostat switch 38 or both call for heat, and does not operate when neither of these switches calls for heat.

The hold-fire control switch 35 of Fig. 1 may be eliminated simply by omitting the same so that its contacts remain apart, as shown in Fig. 5.

The thermo-sensitive coil 46 (Fig. 2) has an end 52 secured to an end of the shaft 45. The shaft 45 is journaled in the shell 47 and extends outwardly therefrom. Mounted on the outer end of the shaft 45 is a bracket 55 in which the mercury tube switches 35 and 36 are attached together as a unit, the bracket being journaled in a suitable bearing 57 in axial alignment with the shell bearing. The bracket 55 carries an arm 58 which is disposed in such relation to the detent 44 that, so long as the fire in the burner 50 is above the dying temperature, and accordingly so long as the wind-box temperature at the coil is above that corresponding to the dying temperature of the fire, the switches 35 and 36 are free to turn without interference from the detent. The detent has a cam face 59 which is engaged by the arm 58 which is turned toward the detent by the cooling coil when the fire is dying, and the detent is thus cammed against the action of its spring until the arm 58 snaps by to the dotted position shown at 58a in Figs. 1 and 3. Now the detent snaps to its outermost or detaining position where it maintains the out-fire switch 36 open, preventing operation of the stoker.

To restart the stoker, it is necessary to reset the out-fire switch 36. This is done by manually pressing back the detent 44 and moving the arm 58 past the same to a position on the other side of the detent so as to close the switch 36, and then allowing the detent to return to its outermost position, the arm being detained in such switch-closing position, as explained above, until the furnace is warm enough to heat the coil 46 sufficiently to hold the switch 36 in closed position without assistance. This may be accomplished by hand in any other desired manner. This may occur when the furnace temperature is only slightly above the dying temperature of the fire. The hold-fire switch 35 will be closed at such time to cause the stoker to operate even if the room thermostat 38 may not be calling for heat, thereby raising the furnace temperature. In the regular operation of the apparatus the fire will keep going, the out-fire control switch 36 opening to stop the stoker only in case the fire dies, whether through accident or intent, as has been explained.

Fig. 6 shows a circuit like that of Fig. 1 but with the hold-fire switch 35 and the out-fire switch 36 actuated by gas instead of by a thermo-sensitive coil.

A bellows 60 communicates by means of a tube 61 with a cylinder 62 mounted in a casing 64 secured in the wind-box 49 about a burner 50. The bellows, tube and cylinder form a closed unit containing gas 68. The bellows carries a shaft or rod 70 having a pin and slot or other suitable connection 71 with the arm 58 to swing it about the staff 45a for controlling the hold-fire and out-fire switches 35 and 36 as will be understood from the description of Figs. 1 to 3.

Fig. 7 illustrates still another system having hold-fire and out-fire controls. The operation of this arrangement is like that of Fig. 6, except that the hold-fire switch 35a is clock-controlled and therefore calls for heat at regular intervals

instead of being dependent on the temperature of the furnace wind-box.

Fig. 8 shows an arrangement similar to that of Fig. 5 but operating through a snap switch 73 and a gas-actuated bellows 60. In this form the rod 70a extending from the bellows 60 carries a contact 74 insulated as at 75 and electrically connected in the relay control circuit as at 77. A blade 78 is urged by a spring 79 toward the contact 74 and is limited in its movement in that direction as by a suitable stop 81. The stop may be arranged to open the switch 73 at a wind-box temperature of, say, 60° F., or may be adjusted to open the switch at any other desired temperature.

Fig. 9 shows diagrammatically an out-fire control switch 84 comprising a mercury thermometer 85 having a graduated column 86 from which, at suitable out-fire control wind-box temperature graduations, extend metallic contacts 88 and 89 in such manner as to have electrical contact with the mercury and provide a switch which closes when the mercury reaches the upper contact 89 and opens when the mercury leaves the upper contact 88. The operation is evident from the foregoing. If desired, two or more upper contacts may be employed or a single contact 89 made adjustable longitudinally of the column 86 as shown to obtain any desired temperature lag between the room thermostat 38 and the out-fire switch 84.

Fig. 10 shows an installation in which is incorporated hold-fire and low limit controls, and a device for giving an alarm when the low limit switch is open. In this arrangement, I provide a double blade snap action room temperature responsive switch instrument generally indicated at 95 and comprising the operating room thermostat switch 38 and low limit and signal alarm switches 96 and 97 and a movable blade 98 common to the switches 96 and 97. In parallel with the operating thermostat switch 38 is a hold-fire switch 35a. The devices 35a and 95 may be held in a compact housing or panel 100 in the room or other space to be heated. The low limit switch 96 is in a circuit containing the relay coil 37, the transformer secondary coil 34, the operating thermostat switch 38 and the hold-fire device 35a, and the alarm switch 97 is in a circuit containing an interrupter 102, a bell 103 or other suitable alarm, a battery 104 and a hand switch 106. The interrupter is optional. A telltale lamp 107 may be provided on the panel 100.

Let it be assumed that the normal maximum room temperature is 75° and that the operating room thermostat 38 operates on a temperature differential of, say 1½° F. The thermostat 38 accordingly will be adjusted or set to open at a room temperature of 75° F. and close at a room temperature of 73½° F. The device 95 may be adjusted or set so that the low limit switch 96 will remain closed until the air in the room drops to any desired temperature, say, 71° F., for example. When the air in the room drops to the selected temperature, i. e., 71° F., whether due to shearing of the stoker shear pin, an empty coal bin, electricity failure, clinker and ashes obstructing further fuel feed, transmission failure, the death of the fire, an open window in the room, or any other cause, the low limit switch 96 opens and the blade 98 snaps over, closing the alarm switch 97. When the switch 96 opens, the relay coil 37 is de-energized and the relay switch 41 opens, stopping the stoker 42. The closing of the switch 97 starts ringing of the bell 103.

and causes the lamp 107 to light, which calls attention to the fact that something is amiss so that an attendant may take care of the matter without delay. If desired, the bell 103 and lamp 107 could be connected to the feed line instead of being energized by a battery as shown. The ringing of the bell may be stopped as by opening the hand switch 106. The temperature levels and differentials governing the operation of the switches 38, 96 and 97, and the temperature lag between the closing of the switch 38 and the opening of the low limit switch 96 may be varied as desired, as will appear.

When the apparatus has been repaired or otherwise properly attended to, the fire is rekindled, if necessary, and the blade 98 is manually moved to close the low limit switch 96 so that if the room thermostat 38 or fire pilot 35a is calling for heat the stoker will again be operated. When the blade 98 is so moved, the attendant closes the hand switch 106. The blade 98 is held by hand or by a hand switch device 106 in the last mentioned position until the temperature of the room reaches or exceeds 73½° F., affording a temperature lag of 2½° F. between the opening and closing of the switch 96, or whatever the selected temperature and lag might be, whereupon it will be unnecessary to hold the blade since the instrument is so adjusted that at or above that temperature the blade will automatically close the switch 96. If desired, a catch 44a may be employed to hold the blade 98 in position to close the switch 96 while the attendant is rekindling the fire or making such repair or adjustment as may be necessary for the continued operation of the apparatus, and until the selected temperature at and above which the switch 96 is automatically closed is reached, whereupon the attendant may secure the catch 44a in inoperative position.

The arrangement appearing in Fig. 11 is identical with that in Fig. 10 except that it relates to a gas or oil burner and thus has no hold-fire device. The operation of the apparatus of Fig. 11 is identical with that just explained, except of course that a gas valve or pump switch and an igniting device are operated instead of a stoker. This low limit and alarm device could operate for any reason, including failure of fuel supply, drop in the fluid pressure, etc. A gas burner installation is shown, and comprises a solenoid 110 controlling a valve 111 (or pump switch if liquid is used) in a fuel conduit 112, the valve being urged to close by a spring 114. The conduit 112 leads to a torch nozzle 115 from which the fuel 116 discharges, air being supplied as at 118 by a fan 119 or other suitable means. The discharged fuel is ignited by a sparking device 120 or other suitable means. This device may comprise points 122 urged apart by a spring 123 and brought together intermittently as by a rotating cam 124.

When the switches 38 and 96 are closed, the relay switch 41 is closed, energizing the solenoid to open the valve 111, and also energizing the sparking device 120 through a transformer 126, igniting the fuel from the nozzle 115. The burner fan 119 and circulating fan or blower 128 are also dependent on the switch 41. A time delay relay 130 may be placed in series with the blower 128 in order to prevent operation of the blower until after the furnace has become warm (usually about three or four minutes). Should the fire go out by accident, the cold air 118 delivered by the burner fan 119 will cool the furnace and

hence the room rapidly, so that the low limit switch 96 will open and hence the spring 114 will close the fuel valve 111 before any substantial amount of fuel has been fed unburned. At the same time, the alarm switch 87 closes. After suitable repair or other needed attention, the attendant holds the out-fire switch 86 closed as explained above for a suitable length of time until the furnace is again sufficiently warm to cause the room temperature to automatically close the low limit switch 96, whereupon the attendant need not further hold the switch 86 closed.

Had the fuel failed to ignite upon starting, the attendant would immediately have noticed this and have released the out-fire switch to open position, so that he could give attention to repair or adjustment.

Another feature of my invention concerns an improved tell-tale thermostat mechanism affording accurate instead of hit-or-miss adjustments of "on" and "off" temperatures and temperature differentials and adapted for three-wire or two-wire use as desired. For the purpose of illustration the three-wire adaptation is here shown and described. This thermostat instrument, illustrated in Figs. 12, 13 and 14 and designated generally by the numeral 95, is of the double blade type and comprises a base or body 135 on which is rotatably mounted a dial 136 bearing graduations 137 which may designate degrees Fahrenheit. A fixed mark or indicator on the casing or cover, described below, or on the base or other stationary part indicates the reading of the dial. The dial 136 has an arcuate cam or ramp 142, slidable relative to and engaging a screw 144 adjustably carried by a strap 145, which may have graduations 146 calibrated in degrees Fahrenheit if desired. A pointer 148 rotatable with the screw is adapted to overlie the graduations 146.

Thermo-responsive elements 151 and 152 are connected as at 154 with the arms 156 and 157, respectively, of a strap 159 to leaf springs 160 anchored to bosses 161 on the base as at 162. Carried and insulated as at 163 from the thermo-responsive elements are blades 165 and 166, respectively. The blade 165 is cooperative with a magnet 168 and has a contact 169 cooperative with an adjustable contact 170 to provide the low limit control switch 96 and with a relatively fixed contact 171 to provide the signal switch 87. The blade 166 is cooperative with a magnet 172 and has a contact 174 cooperative with an adjustable contact 175 to provide the operating room thermostat switch 38. The contact 175 may be formed on a screw for the purpose of adjustment and may carry a pointer 176 movable relative to graduations 177 to increase or decrease the temperature differential in the operating room thermostat 38. A spring 178 holds the contact 175 in the desired adjustment.

It will be observed that the arms 156 and 157 of the strap or bracket 159 may be so relatively inclined or offset that there is an initial predetermined lag between the engagement of the contact blade 166 with the contact 175 and the engagement of the blade 165 with the contact 170. This lag can be varied by the adjustment of a screw 180 having its head engaged with the lower arm of the element 151 and its shank threaded in the strap 159, said element being formed of spring metal. It is evident that, once the contacts 170 and 175 are set, a raising of the blade 165 will prolong its engagement with the contact 170, thereby increasing the temperature lag between the closing of the operating room thermo-

stat switch 38 and the opening of the low limit control switch 96, the alarm switch 87 closing upon the opening of the switch 96. Of course the instrument is set so that both of the contacts 170 and 171 can never be engaged simultaneously, and preferably is set at a temperature lag of about $2\frac{1}{2}$ ° F. between the closing of the operating switch 38 and the opening of the low limit control switch 96, although the lag may be varied as is ap-

parent from the foregoing.

Although the blades are independently controlled by their respective thermo-responsive elements, they are movable together simultaneously when the strap 159 is adjusted by the dial 136. When the dial is turned in one direction, the ramp 142 of the dial raises the strap, thereby lowering the blades, and when the dial is turned in the opposite direction, the springs 160 force the strap down the receding ramp, raising the blades.

This simultaneous adjustment of the blades determines the temperature at which the operating room thermostat switch 38 will close, so that, if the temperature lag is, say, $2\frac{1}{2}$ ° F., and the operating switch 38 is set to close at $73\frac{1}{2}$ ° F., it is known that the low limit switch 96 will open at 71 ° F., whereupon the bell switch 87 will close.

The hand switch 186 for turning off the signal and rendering the mechanism operative for heating or other air conditioning purposes, as when the fire is being started, is shown diagrammatically in Figs. 10, 11 and 14. Actually, it may comprise means for opening the bell switch 87 and closing the low limit control switch 96. To this end, as shown in Figs. 12 and 13, I may provide a lever 185 pivotally and preferably tightly mounted as at 186 and having an indicating handle 188 and an operating arm 189 engageable with a spring strip 191 or other suitable part carried as by the blade 165. By moving the handle 188 in the "Off" direction the arm 189 rides against the strip 191 and shifts or springs the bottom of the strip to a higher position as shown in dotted lines in Fig. 13, thereby maintaining the blade 165 out of engagement with the contact 171 and holding the alarm switch 87 open and the low limit switch 96 closed. The tight mounting of the lever 185 and/or the spring pressure of the shifted strip prevents accidental movement of the lever.

If the bell 183 rings, the telltale lamp 107 lights. By swinging the handle 188 in the "Off" direction, the bell is stopped and the lamp turned off, and the low limit switch 96 closes. After the trouble has been adjusted and the room temperature is raised to normal, the lever handle may be returned to "On" position, which is normal for signal operation. Of course, by leaving the handle at all times in "Off" position, the device operates as an operating thermostat without the signal control.

In the event that the dial 136 is set at, say, 75 ° F., the temperature at which the operating room thermostat switch 38 is desired to open, but the user is under the impression that the switch 38 actually opens at 74 ° F., for example, then by turning the pointer 148 (which rotates with the screw 180) any predetermined number of graduations to the right as seen in Fig. 12, i. e., in a direction to raise the strap 159, he will lower the blades 151 and 152 to such an extent as to retard by one degree the opening of the room thermostat switch 38. The device is similarly calibrated by turning the pointer 148 to the left,

to advance the opening of the switch 38. These calibrations do not affect the lag between the opening of the switch 38 and the opening of the out-fire switch 96. This construction makes possible an immediate correction of error or change to the satisfaction of the user, and is a distinct improvement over previous types, which require a cut-and-try method of correction.

The base may be attached in any suitable manner to a wall plate 195 which itself may be suitably mounted on a wall, the plate carrying the tell-tale lamp 107, if desired. Said plate may have pins 195a engageable in diagonally opposite recesses in the base 135 to maintain them in proper relation.

The dial 136 has a central hole 200 (Fig. 18) aligned with a threaded hole 201 in the base 135, and a screw 202 is threaded in said hole and has an enlargement 203 resting on the base and extending through the hole 200, said enlargement journaling the dial. The head 205 of the screw overlies the bored portion 206 of the dial and lies within the cam 142 but does not interfere with the rotation of the dial by the hand, which can conveniently engage the milled edge 207 of the dial. The spring pressure of the follower 144 on the gently sloping portion 208 of the cam 142 prevents accidental turning of the dial while permitting hand adjustment of the dial. The dial may be locked in the desired position of adjustment as by a plate 210 anchored by a screw 211 threaded to the base 135, the plate having an end 212 fulcruming on the base and a clamp portion 213 adapted to be frictionally clamped against the dial by the screw so tightly as to securely lock the dial. The screw 211 is so arranged as to be inaccessible when the cover 215, hereinafter more fully described, is in place. The plate 210 is prevented from shifting off the dial by abutments 216 and 217 straddling the same.

The base 135 has a ledge or shelf 220 of curved outline conforming to the curvature of the dial 136 and spaced from the back 221 of the base, the shelf being substantially flush with or projecting slightly beyond the edge 207 of the dial to afford a support for the projecting part of the dial and protection for the edge of the dial without interfering with free access of the finger to the edge of the dial to adjust the latter. The shelf adjacent the dial may have a mark or datum point 222 for indicating the reading of the dial. The cam is cooperative throughout the entire 360° with the follower 144, the dial being rotatable continuously in each direction. The relatively steep portion 223 of the cam subtends the ungraduated part of the dial so that when the follower 144 is thereon it will not affect desired adjustments.

The cover 215 is shaped to enclose the base 135 and the thermostat mechanism mounted thereon (Figs. 12 and 13), and has a slot 225 through which the shelf 220 and superposed portion of the dial 136 are adapted to project, the slot being sufficiently wide to provide clearance to enable the slotted portion of the cover to be readily assembled with and disassembled from the shelf and dial notwithstanding tilting of the cover as shown in dotted lines in Fig. 13 to accomplish these results.

The cover has a longitudinal depression 227 in the front wall 228 thereof, said depression being open at its upper and lower ends as shown at 229 and 230, the bottom opening being flared as at 231 to facilitate insertion of the small end

232 of a thermometer 233, and the depression being of such depth that the thermometer is readily accommodated and slideable therein to engage behind said front wall above and below 5 said depression so as to be protected by the cover from injury. The front entrance to the depression is preferably flared forward, providing one or more temperature graduated surfaces 235 with the graduations 236 located adjacent the thermometer for easy reading thereof. One of the 10 graduations may be emphasized, as at 237, adjacent which a mark or scratch 237a on the thermometer known by test to be reached by the liquid therein at the temperature designated by 15 the reading at 237 is placed when the thermometer is adjusted in the depression. Upon such adjustment of the thermometer, cement 238 is applied to the stem of the thermometer and the inner portions of the ends of the depression, 20 so as to securely fasten the thermometer in proper position, the cement being concealed from the outside.

Air holes 239 may be provided at various parts of the cover to insure free access of the atmosphere to the responsive instrumentalities. The 25 hole indicated at 240 is aligned with the depression 227 and is of a width to permit the bulb 240a of the thermometer to pass therethrough so that the thermometer may be inserted and 30 adjusted, or, the hole 240 may be made narrower than the bulb, in which event the material at the sides of the hole will yield elastically, as when made of plastic molding, to enlarge the hole to enable the bulb to pass therethrough.

The cover may have a slot 241 in the end 242 thereof opposite the slot 225, to slip over the shank 243 of a screw 244 at the corresponding end of the base 135, the screw being adapted to be tightened so that its head 246 frictionally engages the cover when the dial 136 and shelf 220 project through the slot 225, to securely and releasably hold the cover in proper assembly with the base (Fig. 13).

The cover may be suitably reinforced as by one 45 or more preferably integral ribs 248.

It will be seen from the foregoing that I have provided by simple means a control mechanism whereby in the event any part of the heating or 50 conditioning system goes out of order, as, for example, if the stoker shear pin becomes broken, or the hopper is empty, or the motor overload is cut out or the electric current is interrupted, or the fire is dirty, or a fuse is blown, or for any reason whatever the fire becomes cool or dies, 55 the feed of fuel will be stopped and, in accordance with an additional feature of the invention, a signal will be given in such manner as to call immediate attention to the fact that something is out of order, in order that repairs may 60 be made without serious delay.

It will further be noted that I have provided an improved dial and cam and mounting therefor, together with a cover of simple construction which is readily mounted and removed, said cover 65 protectively carrying a thermometer and being so constructed as to enable the thermostat to be readily positioned and secured in the desired relation to the temperature graduations on the cover. The base, mounting plate, cover and cam, as well as other parts, may be formed of molded plastic or other suitable material.

Various modifications may suggest themselves to those skilled in the art without departing from the spirit of my invention, and, hence, I do not 70 wish to be restricted to the specific form shown

or uses mentioned, except to the extent indicated in the appended claims, which are to be interpreted as broadly as the state of the art will permit.

I claim:

1. A space conditioning system, comprising a conditioner, means for supplying said conditioner with fuel to enable said conditioner to supply a conditioning medium to said space, means operative in response to a preselected supply-demanding condition of said space to operate the first mentioned means and to a preselected satisfied condition of said space to render said first mentioned means inoperative, and means operative in response to a preselected supply-demanding condition of said space beyond the range defined by the first two conditions aforesaid to render the first mentioned means inoperative.

2. A space conditioning system, comprising a conditioner, means for supplying said conditioner with fuel to enable said conditioner to supply a conditioning medium to said space, means operative in response to a preselected supply-demanding condition of said space to operate the first mentioned means and to a preselected satisfied condition of said space to render said first mentioned means inoperative, means operative in response to a preselected supply-demanding condition of said space beyond the range defined by the first two conditions aforesaid to render the first mentioned means inoperative, and a signal device automatically operated upon operation of the last mentioned means.

3. A space conditioning system, comprising a conditioner, means enabling said conditioner to supply a conditioning medium to said space, means operative in response to a preselected condition of said space to operate the first mentioned means and in response to another preselected condition of said space to render said first mentioned means inoperative, means operative in response to a preselected condition of said space beyond the range defined by the first two conditions aforesaid to render said first mentioned means inoperative, a signal device automatically operative upon operation of the last mentioned means, manually releasable means for preventing reoperation of said last mentioned means, and means for rendering said signal device inoperative without rendering said last mentioned means operative.

4. A space heating system comprising a furnace, means for feeding fuel to said furnace, fuel feed control means responsive to predetermined upper and lower temperatures of said space for respectively stopping and causing operation of said fuel feeding means, temperature responsive safety means disposed, when an abnormally low space temperature obtains, in a position rendering said fuel feeding means inoperative irrespective of said control means, whereby the attendant may have an opportunity to correct the cause of the abnormal temperature without danger resulting from fuel feed if the fire were out, said safety means being disposed, when a space temperature intermediate said lower and abnormal temperatures obtains, in a second position enabling said control means to resume control of said fuel feeding means, said safety means being manually movable to its second position while said abnormal space temperature obtains and in opposition to the influence of said abnormal space temperature on said safety means,

manually releasable means for retaining said safety means in said second position, whereby control of said fuel feeding means by said control means may be resumed after correction of said cause and while said abnormal temperature still exists, a signal device rendered operative when said safety means is in the first mentioned position, and means for rendering said signal device inoperative without changing the position of said safety means.

5. A space heating system comprising a furnace, means for feeding fuel to said furnace, fuel feed control means responsive to predetermined upper and lower temperatures of said space for respectively stopping and causing operation of said fuel feeding means, temperature responsive safety means disposed, when an abnormally low space temperature obtains, in a position rendering said fuel feeding means inoperative irrespective of said control means, whereby the attendant may have an opportunity to correct the cause of the abnormal temperature without danger resulting from fuel feed if the fire were out, said safety means being disposed, when a space temperature intermediate said lower and abnormal temperatures obtains, in a second position enabling said control means to resume control of said fuel feeding means, said safety means being manually movable to its second position while said abnormal space temperature obtains and in opposition to the influence of said abnormal space temperature on said safety means, manually releasable means for retaining said safety means in said second position whereby control of said fuel feeding means by said control means may be resumed after correction of said cause and while said abnormal temperature still exists, and a signal device rendered operative when said safety means is in the first mentioned position.

6. A space heating system comprising a furnace, means for feeding fuel to said furnace, fuel feed control means responsive to predetermined upper and lower temperatures of said space for respectively stopping and causing operation of said fuel feeding means, temperature responsive safety means disposed, when an abnormally low space temperature obtains, in a position preventing said control means from controlling said fuel feeding means, whereby the attendant may have an opportunity to correct the cause of the abnormal temperature without danger resulting from fuel feed if the fire were out, said safety means being disposed, when a space temperature intermediate said lower and abnormal temperatures obtains, in a second position enabling said control means to resume control of said fuel feeding means, means manually operable to resume and maintain operation of said fuel feeding means while abnormal space temperatures obtain, said manually operable means being releasable so as not to interfere with operation of said safety means when normal temperatures are again followed by an abnormally low temperature, a signal device rendered operative when said safety means is in its first position, and manually operable means for rendering said signal means operative and inoperative without changing the position of said safety means.

7. A space heating system comprising a furnace, means for feeding fuel to said furnace, fuel feed control means responsive to predetermined upper and lower temperatures of said space for respectively stopping and causing operation of said fuel feeding means, temperature responsive safety means disposed, when an abnormally low

space temperature obtains, in a position preventing said control means from controlling said fuel feeding means, whereby the attendant may have an opportunity to correct the cause of the abnormal temperature without danger resulting from fuel feed if the fire were out, said safety means being disposed, when a space temperature intermediate said lower and abnormal temperatures obtains, in a second position enabling said control means to resume control of said fuel feeding means, means manually operable to resume and maintain operation of said fuel feeding means while abnormal space temperatures obtain, said manually operable means being releasable so as not to interfere with operation of said safety means when normal temperatures are again followed by an abnormally low temperature, and a signal device rendered operative when said safety means is in its first position.

8. A space heating system, comprising a heater, means for feeding combustible fuel to said heater to enable said heater to supply a heating medium to the space, means operative in response to pre-selected heat-demanding space temperature to operate said fuel feeding means and to a pre-selected satisfied space temperature to render said fuel feeding means inoperative, means responsive to an abnormally high heater temperature to render said fuel feeding means inoperative, and means for averting the hazards of personal and property damage due to fuel feed to said heater under dead fire conditions, said averting means being operative in response to a preselected heat-demanding space temperature below the aforesaid heat-demanding space temperature to render said fuel feeding means inoperative.

9. A space heating system comprising a furnace, means for feeding fuel to said furnace, fuel feed control means responsive to predetermined upper and lower temperatures of said space for respectively stopping and causing operation of said fuel feeding means, temperature responsive safety means disposed, when an abnormally low space temperature obtains, in a position preventing said control means from controlling said fuel feeding means, whereby the attendant may have an opportunity to correct the cause of the abnormally low space temperature without danger resulting from fuel feed if the fire were out, said safety means being disposed, when a space temperature intermediate said lower and abnormally low temperatures obtains, in a second position enabling said control means to resume control of said fuel feeding means, said safety means being manually movable to said second position after the cause has been corrected and while abnormally low space temperatures still obtain, means manually movable to a position in which it retains said safety means in said second position, whereby to resume and maintain operation of said fuel feeding means under the control of said control means while abnormally low space temperatures obtain, said manually movable means being releasable so as not to interfere with operation of said safety means when normal space temperatures are again followed by an abnormally low space temperature, and a signal device controlled by said safety means and rendered operative when said safety means moves to its first position.

35

ARTHUR V. SAMPSEL.
